(57) **CLAIM**

The ornamental design for a pergola roof support structure design, as shown and described.

DESCRIPTION

FIG. 1 is a front, elevation view of a new pergola roof support structure design.

FIG. 2 is a top, plan view of said pergola roof support structure design.

FIG. 3 is an enlarged partial, top, plan view of said pergola roof support structure design.

FIG. 4 is an enlarged partial, side, plan view of said pergola roof support structure design.

FIG. 5 is an enlarged partial, front, plan view of said pergola roof support structure design; and,

FIG. 6 is an enlarged partial, perspective view of said pergola roof support structure design.

The broken lines are for illustrative purposes only and form no part of the claimed design.
